United States Patent Office.

GOTTLIEB FRIDERICH FISCHER AND ALEXANDER WHELAN, OF WASHINGTON, DISTRICT OF COLUMBIA, ASSIGNEES TO THEMSELVES AND JOSEPH KELLEY, OF SAME PLACE.

Letters Patent No. 104,294, dated June 14, 1870.

IMPROVEMENT IN HINGES.

The Schedule referred to in these Letters Patent and making part of the same.

We, GOTTLIEB FRIDERICH FISCHER and ALEXANDER WHELAN, both of the city and county of Washington, in the District of Columbia, have jointly invented an Improvement in Hinges, of which the following is a specification.

The object of this invention is to adapt the pintle of a hinge to fall automatically, and thereby lock the leaves together and hold immovably the door, shutter, or gate to which it is applied, when the same is thrown to its open position.

Figure 1 is a perspective view of a hinge, the parts being represented as they appear when the door, shutter, or gate is open.

Figure 2 is a similar view, showing the hinge as closed.

Figures 3, 4, 5, and 6 are sectional views.

Similar letters of reference indicate corresponding parts in the several figures.

In order that others skilled in the art to which our invention appertains may be enabled to fully understand and use the same, we will proceed to describe it, in connection with the drawing.

A and B may represent the leaves, and C the pintle or axis-pin of a hinge, which is constructed after any desired pattern, but which has its sockets and pintle so formed that the pintle may slide or move longitudinally within the sockets, for the purpose of locking the leaves together when open, and releasing them from each other when they are to be closed.

The sockets or bores K may be drilled or cast in the cylindrical enlargements of the leaves A, B in the usual way.

The upper socket is closed at top; the lower one is open throughout.

The axis-pin C fits within the sockets snugly enough to properly maintain the relative positions of the leaves, and yet it is free to slide vertically therein when the leaves are opened out, so as to stand in the same plane.

F is a spline or rib, occupying a longitudinal position upon, and projecting rigidly from, the axis-pin C.

E and G are grooves opening into the sockets K, and adapted to accommodate the spline F.

D is a ball or weight, formed or screwed upon the lower end of the axis-pin C.

The operation may be set forth in few words.

So long as the hinge is closed, or only partially opened, the axis-pin retains its highest position, and the spline F is completely housed in the groove G of the upper socket. But, when the hinge is completely opened, the two grooves G and E are brought into line with each other, forming one continuous groove; and, as the spline has then lost its seat upon the shoulder H, the weighted axis-pin C descends, carrying the spline F downward into the groove E of the lower socket. The bottom of the groove E forms a new seat for the spline, and the downward movement of the axis-pin is limited thereby. Thus, the spline is caused to occupy both grooves, and the hinge to

lock itself in the open condition, in order to hold open the door, gate, or shutter to which it may be applied. When the hinge (or the door, gate, or shutter) is to be closed, the axis-pin is raised by hand till the spline F is free of the groove E of the lower socket.

It is obvious that modifications may be made in several particulars. Thus, a spring might fill the office of the weight D in securing the descent of the axis-pin, or the pin itself may be sufficiently weighty to effect the object. Any kind of joint other than that shown may be formed at I, to more effectually exclude water, or to subserve other useful purpose.

It will be seen that the groove E, having parallel sides, is located in the lower section of the hinge, in such a position as to receive the spline of the pintle, and lock the hinge both ways, thus dispensing with the necessity of having springs or other devices between the shutter and the wall to prevent rattling. The annular seat H, it will also be observed, is perfectly level, and of only sufficient bearing for the end of the spline to support it in opening and closing the shutter, while the stop N, in the groove E, limits the descent of the pintle; thus, the groove, so arranged, performs three functions: to lock the shutter in both directions, and to hold the pintle within the knuckles when so locked, all inclosed in the fixed knuckle of the hinge.

We are aware that hinges, of the same general principle as ours, have been made and constructed on the same general plan, but, in these hinges, the groove E is replaced by a notch on the edge of the bearing H, which has an inclined surface, on which the spline rests, so that the pintle descends gradually to its place, and is locked only in one direction. By means of the groove E we are enabled to lock the hinge and pintle so that they cannot move in either direction.

Claim.

We claim as our invention—

1. The arrangement of the grooves E, having parallel sides, and G, on the interior of the knuckles, of the fixed and movable leaves of the hinge, in combination with a spline, F, formed on the pintle C, the parts being entirely inclosed within the knuckles, as herein shown, and for the purpose described.

2. The combination in a hinge of a locking and unlocking device, consisting of a cylindrical pintle, C, with its spline F and weight D, having a vertical and a swiveling movement, the interior grooves E, having parallel sides, and G, the annular seat H, and the stop N, all constructed, arranged, operating, and forming part of the knuckles of the hinge, as herein shown and described.

G. F. FISCHER.
A. WHELAN.
